UNITED STATES PATENT OFFICE.

GEORGE W. HOPKINS, OF CLEVELAND, OHIO.

FILM DRIER.

Application filed December 7, 1927. Serial No. 238,390.

This invention relates to a drier adapted particularly for drying photographic films, especially those made by Roentgenologists. Before such films can be interpreted with safety and accuracy, it is essential that they be thoroughly dried, and the time required for this operation frequently takes from one to twenty-four hours employing apparatus at present available for drying purposes. This lapse of time between exposure and interpretation hinders the Roentgenologists in their work and oftentimes is disadvantageous to the subject of the film.

A number of methods for drying films are now employed but are objectionable in that the time required for drying the film is entirely too long, or with the quicker methods heat is employed which is quite dangerous inasmuch as the films are composed of very inflammable and explosive materials. However, with the above methods of drying the result is very unfavorable as the minimum time required for drying usually exceeds one hour, and where a great number of exposures are made during a day, this delay materially handicaps the work of the Roentgenologists.

The principal object of the present invention is, therefore, to provide a film drier which will greatly reduce the time now required to dry films even with the best apparatus at present available and which will dry the films with absolute safety. More particularly, it is one of the chief aims of the invention to provide a film drier which enables a film to be dried and, therefore, interpreted within a few minutes after exposure and development so as to dispense with the necessity of waiting a relatively long time for the film to dry, and, as a result avoid unnecessary delays which are often dangerous.

In carrying out the invention, drying of the film is accomplished exceedingly quickly and efficiently by supporting the film in preferably a vertical position and directing currents of air under pressure upon opposite sides of the film simultaneously and proportionately distributed over the entire surfaces. This causes the film to be dried simultaneously and quickly throughout its entire area without staining or otherwise injuring the film in any manner.

A further object of the invention is to provide a drier adapted for drying a plurality of films simultaneously and practically as quickly as an operator can remove the dried films

and replace them with films to be dried. In carrying out this feature of the invention, it is an object to provide an efficient drier of the type referred to and at the same time provide a drier which is compact and occupies very little floor space, which in itself is a considerable advantage over the apparatus at present available and employed.

Another object of the invention is the provision of means whereby the air in passing therethrough is deflected or broken up into a plurality of streams of air and caused to be distributed in proper proportions and pressures over the various surface areas of the film to thereby effect simultaneous drying of the film.

With the objects above indicated and other objects hereinafter explained in view, my invention consists in the construction and combination of elements hereinafter described and claimed.

Referring to the drawings:—

Fig. 1 is a front elevational view of a drier embodying the present invention and partly shown in section.

Fig. 2 is a vertical cross-sectional view taken on line 2—2 of Fig. 1.

Fig. 3 is a horizontal cross-sectional view taken on line 3—3 of Fig. 1.

Fig. 4 is a fragmentary vertical sectional view showing the relative position of a film within the drier.

Fig. 5 is a fragmentary view of the front lower portion of the drier showing the manner of supporting the films to be dried.

In the drawings, I have illustrated a pair of driers adapted for drying films according to my method for the reason that this arrangement has proven most efficient in actual practice, although it should be understood that I am not to be limited to this precise structure inasmuch as any number of films may be dried in the manner to be described and various types of apparatus may be provided for carrying out the principle involved.

The driers shown in the drawings consist of a pair of side members 10 suitably spaced apart, and secured thereto is a top member 11 and a bottom member 12, the latter being provided with legs 13 for suitably supporting the driers. A vertically extending central partition 14 is secured to and extends transversely of the top member 11 and bottom member 12, dividing the structure into substantially two separate driers and the description of the con-

struction of one of these driers will suffice for both. This arrangement of the driers forms no part of the present invention and is a matter of convenience in constructing the drier 5 and utilizing as little floor space as possible. Each of the driers is provided with a horizontally positioned partition 15 secured to the side members 10, thereby dividing the drier into an upper or air distributing compartment 16 and a lower or film drying compartment 17, the purpose of which will be later described.

The upper compartment 16 has a front member 18 and a back member 19 secured to 15 the end members 10 and the top and horizontal partitions 11 and 15 respectively so as to entirely enclose and substantially seal the air distributing compartment 16.

The horizontal partition 15 is provided with 20 a plurality of elongated openings 20, as clearly shown in Fig. 3, to permit the air which is introduced into the distributing compartment 16 to pass out therefrom and into contact with the films to be dried.

25 The lower or film drying compartment 17 is provided with a plurality of hollow units 21 suitably spaced apart as shown in Fig. 5, in which space a film is adapted to be supported. Each of these units 21 is divided by 30 a vertical partition 23, thereby providing a pair of air chambers 24, one on each side of said partition, which communicate respectively at their upper portions with the openings 20 in the horizontal partition 15. The side 35 walls 25 of the units have transverse apertures 26 substantially centrally thereof, and extending radially therefrom are a plurality of slots 27. These slots are so arranged that the required proportional distribution of the air 40 over the various areas of the films is produced.

At the lower portion of each partition 23 and upon opposite sides are tapered surfaces 27' which tend to assist in the distribution of the air. To direct the air from the distributing compartment 16, a pair of deflectors or baffles 28 are secured to the lower portion of the front and back members 18 and 19 and extend downwardly towards the openings 20, as clearly shown in Fig. 2. Depending from each end of the openings 20 and secured within the upper portion of each air chamber 24 are members 30 forming with the partition 23 and the side members 25 a restricted throat through which the air passes 55 enroute to the air chambers 24 and thence to the films.

The films, one of which is indicated by the reference numeral 31, are supported in a suitable wire frame 32 which slides in grooves 60 or guideways 33 supported between the side members 25 at the top and bottom. The film is substantially the same size as the extremities of the radial slots 27 so that the air is directed proportionately over the entire area 65 of the film, and, because of the arrangement

of the air chambers 24, upon both sides of the film at once, thereby causing the film to be dried over both of its entire surfaces simultaneously.

To further effect the proper distribution 70 of the air from the distributing compartment 16 to the air chambers 24, a plurality of baffles 34 are secured, as shown in Fig. 2, within the air chambers adjacent the restricted throat. 75

Air is delivered to the distributing chamber 16 by rotary blowers 35 actuated by a motor or other means (not shown), through an opening 36 in the top member 11. The air within the distributing compartment is maintained under pressure greater than atmospheric and consequently is forced outwardly through the openings 26 onto both sides of the film simultaneously and proportionately over the entire 80 surface, resulting in the drying of the film in a few minutes and without staining or injuring the film in any manner.

In the operation of the drier, the blowers 35 are started and an air pressure is built up 90 in the distributing chamber 16. The films 31 are loaded in their holders 32 and together are slid into the grooves or guideways 33 until the film is properly positioned within the space 21 adjacent the openings 26 and radial slots 27. The air under pressure greater than 95 atmospheric is forced through the openings 20 in the horizontal partition 15 into the air chambers 24 and thence through the openings 26 and radial slots 27 onto both sides of the films 31. Due to the arrangement of the slots 100 27 and the baffles 34, the air is deflected and distributed in proper proportions, under proper pressures over the various surface areas of the films. As a result, the entire area 105 is dried simultaneously and without staining or injuring the film in any manner. 105

After the drying compartment 17 is once loaded with films, each film is completely dried in a few minutes or about as fast as the operator can remove a dried film, reload the 110 holder, and replace it in the drying compartment.

It will be understood by those skilled in the art that a great amount of time is saved by employing an apparatus which operates according to the method above described, and because of the compactness of the device, very little floor space is required for a large production. 115

Having thus described my invention, I 120 claim:

1. The method of drying films which consists in directing air onto both sides of the film and proportionately distributing the air over the film surfaces to cause the various surface portions of the latter to be dried simultaneously. 125

2. The method of drying films which consists in directing air above atmospheric pressure onto both sides of the film and propor- 130

- tionately distributing the air under varying degrees of pressure over the film surfaces to cause the various surface portions of the latter to be dried simultaneously.
5. 3. The method of drying films which consists in directing streams of air of different pressures into contact with the surfaces of the film to thereby cause the various surface portions of the film to be dried simultaneously.
10. 4. The method of drying films which comprises subjecting the surfaces of the film to the flow of proportionately distributed air above atmospheric pressure to thereby cause the various portions of said surfaces to be dried simultaneously.
15. 5. The method of drying films which comprises directing air onto both sides of the film and over the various surface portions of the surfaces thereof in proportion as is needed to dry said surface portions simultaneously.
20. 6. The method of drying films which comprises directing air streams onto both sides of the film and against the various portions of the surfaces thereof, the volume of said streams being in proportion as is needed to dry said various portions simultaneously.
25. 7. The method of drying films which comprises directing air streams onto both sides of the film and over the various portions of the surfaces thereof, the pressure of the air supplied to said streams being in proportion as is needed to dry said various portions simultaneously.
30. 8. The method of drying films which comprises distributing air to the various surface portions of both surfaces of the film in proportion as is needed to dry said surface portions simultaneously.
40. 9. In a drier for films and the like, a film holder adapted to support a film, and means for directing a flow of air onto both sides of the film simultaneously, and means for directing and proportionately distributing said flow onto the various portions of the surface area of the film to dry said various portions simultaneously.
45. 10. In a drier for films and the like, a film holder adapted to support a film, means for directing a flow of air above atmospheric pressure onto both sides of the film simultaneously, and means for directing and proportionately distributing said flow onto the various surface portions of both sides of the film to dry said various portions simultaneously.
50. 11. In a drier for films and the like, a drying compartment, means for supporting a film in said compartment, means for directing air onto both sides of said film simultaneously, and means for directing and proportionately distributing the flow of air onto the various surface portions of both sides of the film to dry said portions simultaneously.
55. 12. In a drier for films and the like, an air distributing compartment, means for delivering air to said compartment, a film drying compartment communicating with said distributing compartment, means for supporting a film in said drying compartment, and means for directing and proportionately distributing the air onto both sides of the film to dry the various surface portions of both sides simultaneously.
60. 13. In a drier for films and the like, a drying compartment, means for supporting a plurality of films in said compartment, means for delivering air to said drying compartment on both sides of said supporting means simultaneously, and means for directing and proportionately distributing the flow of air against the various surface portions of both sides of said film to dry said portions simultaneously.
65. 14. In a drier for films and the like, a drying compartment, means for supporting a plurality of films in vertical position in said compartment, and means for directing air streams of different pressures above atmospheric onto the various surface portions of both sides of the films simultaneously.
70. 15. In a drier for films and the like, an air distributing compartment, means for supplying air thereto under pressure, a drying compartment, means for supporting a plurality of films in said drying compartment to be dried, means for admitting air from said distributing compartment to said drying compartment on opposite sides of the supporting means simultaneously, and means for directing and proportionately distributing the air in streams against the various surface portions of both sides of the films simultaneously to dry said various portions at a uniform rate.
75. 16. In a drier for films and the like, an air distributing compartment, means for supplying air thereto under pressure, a plurality of air chambers communicating with said compartment, means for supporting films between said air chambers, and means for directing the air onto the various surface portions of both sides of the films to dry the latter uniformly throughout.
80. 17. In a drier for films and the like, a pair of spaced air chambers, means for supplying air thereto under pressure, means for supporting a film between said chambers, and means for directing the air onto the various surface portions of both sides of the film in proportion as is needed to dry said surface portions simultaneously.
85. 18. In a drier for films and the like, a plurality of air chambers spaced apart, means for supplying air thereto, means for supporting films between said chambers, baffles in said chambers, and discharge openings from said chambers through which said air passes into contact with both sides of said films proportionately.

tionately throughout their surfaces to thereby dry both sides of said films simultaneously.

19. In a drier for films and the like, an air distributing compartment, means for supplying air above atmospheric pressure to said compartment, a plurality of air chambers communicating with said compartment and spaced apart, and means for supporting films between said chambers, said chambers having outlet openings for said air adapted to distribute the latter proportionately over the entire surfaces of the films to thereby dry both sides thereof simultaneously.
- 15 20. In a film drier, a member adapted to be positioned adjacent a film having a substan-

tially central opening and radial slots extending therefrom.

21. The method of drying films which comprises directing a flow of air under pressure 20 onto the surface of a film so as to cause a greater volume of air to flow over those portions of the film surface which have a higher moisture content and a lesser volume of air to flow over those portions which have a lower 25 moisture content, whereby the various surface portions of said film are dried substantially simultaneously.

In testimony whereof, I hereunto affix my signature.

GEORGE W. HOPKINS.
